VENTILATING APPARATUS

Filed Dec. 3, 1935

UNITED STATES PATENT OFFICE

2,074,295

VENTILATING APPARATUS

Henry S. Woodruff, Larchmont, N. Y., assignor
to American Radiator Company, New York,
N. Y., a corporation of New Jersey

Application December 3, 1935, Serial No. 52,668

3 Claims. (Cl. 98—94)

This invention relates to ventilating apparatus, and more particularly to ventilating apparatus of the type suitable for installation in a window opening and which operates to admit and/or exhaust air from a room.

Apparatus of this type heretofore known to me, usually comprises a ventilating unit comprising a casing fixedly mounted on the window sill and having inlet and outlet openings therein connecting the room space with the outside atmosphere. Air moving mechanism is usually mounted within the casing and operates to move the air therethrough. The lower sash rail of the window has a sealing engagement with the casing; and the spaces at each end of the casing, defined by the end of the casing, the adjacent window jamb, the lower sash rail of the window and the window sill, are usually closed by filler blocks having sealing engagement with the elements named and serving to prevent the passage of air between the outside and room space except through the casing.

An object of my invention is to provide a filler block of the above character which is of improved form, is simple and inexpensive to construct and install, and one which is pleasing in appearance.

The invention consists in the novel construction and combination of parts, to be more fully described hereinafter, and the novelty of which will be particularly pointed out and distinctly claimed.

In the accompanying drawing, to be taken as a part of this specification, I have fully and clearly illustrated a preferred embodiment of my invention, in which drawing—

Fig. 1 is a front elevation, showing my improvement as installed in a window opening;

Fig. 2 is an enlarged fragmentary view partially in plan and partially in horizontal section, the view being taken on the line 2—2 of Fig. 1;

Fig. 3 is a vertical section taken on the line 3—3 of Fig. 1;

Fig. 4 is a perspective view showing my improved form of filler block with one end member removed; and

Fig. 5 is a detail elevational view of the inner face of an end member.

Referring now in detail to the construction illustrated, the reference numeral 10 indicates a window sill, the numeral 11 a pair of spaced window jambs, and the numeral 12 the lower or sill rail of a window sash 13 slidably mounted in the jambs. A window ventilator 14 is centrally mounted in the partially opened window and rests on the window sill 10 and has a sealing en-

gagement with the lower sash rail 12 of the window. Insofar as the present invention is concerned, the ventilator 14 may be of any suitable construction. The one here shown comprises a casing 15 secured to the window sill by suitable screws 16 and provided at its front with outlet openings 17, through which air flows into the room. The openings 17 are controlled by adjustable louvers 18 which operate to direct the air to different desired portions of the room or to close the outlet openings. The inlet opening for the air is located at the rear of the casing and fixed louvers 19 are mounted over the inlet opening to prevent the entrance of rain or snow into the ventilator. Suitable mechanism (not shown) may be mounted in the ventilator for admitting fresh outside air into the casing and forcing such air into the room through the louver-controlled outlet openings 17.

The spaces between the ends of the casing 15 and the window jamb 11 are closed by filler blocks 20, there being one filler block for each space. The filler blocks are rectangular in shape and fit within vertical guide channels 21 and 22 secured to the ends of the ventilator and the window jambs, respectively. The upper face of each of the filler blocks is provided with a suitable strip of felt 23, or similar material, for effecting a sealing engagement between the lower sash rail 12 and the block 20. The lower part of the filler block 20 fits tightly against the outside face 24 of the window sill 10 and thereby prevents the passage of air by the block at this point.

In accordance with the present invention, the filler block comprises a top member 25, a bottom member 26, end members 27 and a panel member 28. The top and bottom members 25 and 26 extend between the end of the ventilator and the window jamb and are provided on their opposed or inner faces with longitudinally extending grooves 30. The end members 27 are also provided with longitudinally extending grooves 31 on their inner faces which, when in assembled position, communicate with the grooves 30 to provide a continuous groove lying in a single plane. The top and bottom members and the end members form a hollow rectangular frame fitting the space at an end of the ventilator, and the panel member 28 is securely held in the frame by its outer edges fitting in the grooves 30 and 31.

The end members 27 are provided at each end thereof with tongues 32 which slidably fit in the grooves 30 of the top and bottom members. The front and rear inside corners of the top and

bottom members are beveled as indicated at 33 and the end members are provided at their ends with notches 34 having beveled inside surfaces 35 which engage the beveled surfaces of the top and bottom members and thereby provide smooth joining surfaces between the end members and the top and bottom members. The end members are also suitably beveled at their front and rear inside corners, as indicated at 36, so as to provide 10 with the bevel 33 a continuous bevel to the inside corners of the frame and thereby add to the pleasing appearance of the block 20.

The top member 25 is provided with an upwardly extending flange 37 which extends for the 15 full length thereof and is firmly secured thereto. The outer face of the flange 37 lies in the same plane as the front face of the top member 25. The upwardly extending flange member 37, when in position, lies at the inside of the lower sash rail 20 12 and provides a weatherproof joint therewith.

By reason of the construction just described, a 25 filler block is provided which requires no complex fitting when installed, such as mitering the frame members, or cutting, fitting and applying molding. The filler block is pleasing in appearance and can be made and installed quickly and simply and at a low cost.

This improved filler block construction is admirably suited for the installation of ventilators 30 in windows of varying widths. The ventilators, of course, are of standard dimensions and the distance between the sill and the lower sash rail will therefore remain the same for all windows. Hence, the length of the end members 27 and the 35 height of the panel 28 can be made standard to bridge this distance. The length of the top and bottom members and the panel 28 will vary with the particular width of window and these parts can be easily cut at the time of installation.

40 The filler blocks may be made up for standard heights and for a series of standard lengths. For each installation, filler blocks may be supplied which have the standard length dimension which is greater than and nearest to the length 45 requirement of the spaces, and the blocks cut at the time of installation. Preparatory to installing, the blocks are first disassembled by simply sliding one of the end members out of the grooves 30 and then withdrawing the panel 50 member 28 from the grooves. The top and bottom members 25 and 26 and the panel 28 may then be readily cut to fit the particular dimension between the end of the ventilator and the window jamb. After cutting, the panel may be 55 readily inserted in the grooves and the previously removed end member 27 replaced.

An alternative manner of preparing the filler block for installation is indicated in Fig. 4. The 60 panel 28 of the filler block has been previously cut to the required dimension and reinserted in the frame. The disassembled end member 27 is then readily slid into place, leaving overhanging portions of the top and bottom members. The 65 overhanging portions may then be cut and the filler block placed in the channels 21 and 22.

Insofar as certain of the aspects of the invention are concerned, the filler block may be formed of any suitable material. In the particular embodiment of my invention which is shown on the 70 accompanying drawing, the top, bottom and end members are formed of wood which may be simply and easily grooved and notched in the manner shown. The panel member 28 may be 75 either formed of ply-wood or of glass. In the

commercial product, it is the intention that the 5 filler blocks be furnished to the customer with ply-wood panels, who may substitute glass panels if desired. However, this practice may vary. The upwardly extending flange 37 may be suitably formed of ply-wood, which gives a very strong and sturdy flange that cannot be easily broken.

What I claim and desire to secure by Letters 10 Patent of the United States is:—

1. A filler block for closing the space defined by a window jamb, one end of a ventilator, a lower rail of a window sash, and a window sill; comprising top and bottom members extending between the window jamb and the ventilator at the upper and lower sides of said space, respectively; end members arranged adjacent the window jamb and ventilator, respectively, and connecting the ends of the top and bottom members and forming therewith a substantially rectangular frame bounding said space; the top and bottom members and the end members being each provided with a groove in the inside face thereof and extending for the full length thereof and each groove connecting at its opposite ends with adjacent grooves to provide one continuous groove lying in the same plane; at least one of said end members being provided at its opposite ends with tongues slidably fitting in the ends of the grooves of the top and bottom member, respectively; and a panel of the same shape as the inside of the frame detachably mounted in the frame with its edges slidably received by said grooves. 25

2. A filler block for closing the space defined by the end of a window ventilator, a window jamb, the lower rail of a window sash and the window sill; comprising parallel top and bottom members and parallel end members forming a rectangular frame of substantially the same size as said space and a panel member detachably mounted in the frame; the top and bottom members having a predetermined desired length that will bridge the distance between the end of the ventilator and the window jamb, and each being provided on its inside face with an open-ended groove extending for the full length thereof, and each being provided with beveled front and rear inside corners extending for the full length thereof; each of the end members being of standard length and being provided at their opposite ends with outwardly projecting tongues slidably fitting within the grooves of the top and bottom members, respectively, and with notches at the front and rear sides of the tongues having beveled faces contacting with the beveled corners of the top and bottom members to form a smooth joint between the end members and the top and bottom members; each of the end members being also provided at its inner side with an open-ended longitudinally extending groove which lies in the same plane as the groove of the other end member and the grooves of the top and bottom members; and the edges of the panel member being received by said grooves. 55

3. A filler block for closing the space defined by the end of a window ventilator, a window jamb, the lower rail of a window sash, and the window sill; comprising parallel top and bottom members and parallel end members forming a rectangular frame of substantially the same size as said space and a panel member detachably mounted in the frame; the top and bottom members having a predetermined desired length that will bridge the distance between the end of the ventilator and 70

the window jamb, and each being provided with beveled front inside corners extending for the full length thereof; each of the end members being of standard length and being provided at their opposite ends with notches having beveled faces contacting with the beveled corners of the top and bottom members to form a smooth joint between

the end members and the top and bottom members; each of the end members being also provided with a beveled front inside corner which matches the beveled front inside corners of the top and bottom members.

HENRY S. WOODRUFF.
